(57) **CLAIM**

I claim the ornamental design for a covering for an architectural opening having multiple columns of double cells, as shown and described.

DESCRIPTION

FIG. 1 is an isometric view of a covering for an architectural opening having multiple columns of double cells.

FIG. 2 is an enlarged detail view of area 2 circumscribed within FIG. 1.

FIG. 3 is a left side elevation view of the covering of FIG. 2.

FIG. 4 is a front elevation view of the covering of FIG. 2. FIG. 5 is a rear elevation view of the covering of FIG. 2; and, FIG. 6 is a top plan view of the covering of FIG. 2. The bottom plan view being a mirror image thereof.

The broken lines in the drawings illustrate portions of the article that are not included in the claim. The circular dot-dash-dot broken line in FIG. 1 indicates on the larger figure the viewpoint of the enlarged detail shown in FIG. 2 and forms no part of the claimed design. All other dot-dash-dot broken lines in the drawings depict the boundaries of the claim and form no part thereof.
